EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed November 12, 1923. Serial No. 674,113.

To all whom it may concern:

Be it known that I, EDWARD S. STIMPSON, a citizen of the United States, residing at Hopedale, in the county of Worcester and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms, whereby the filling is replenished from time to time prior to complete exhaustion.

Various kinds of feeler mechanisms have heretofore been suggested for the purpose of either stopping the loom or replenishing the filling when the filling in the shuttle has reached a degree of substantial exhaustion.

It is now the common practice to provide the feeler mechanism with a feeler which enters the shuttle on each detecting beat and contacts with the filling, and when the filling reaches substantial exhaustion the

feeler detects this condition and sets in operation a train of mechanism for replenishing the filling. This constantly recurring contact of the feeler with the filling on each detecting beat is liable to injure the filling,

especially when the filling is of fine count or formed of material such as silk or the like. Since the function of the feeler is to call for a change of filling when that in the shuttle has become substantially exhausted, it is not necessary that the feeler perform its detecting function continuously during the entire period of weaving, but it will suffice for the feeler to perform its feeling function when the filling has ap-

proached the danger point, and initiate replenishment of filling when that in the shuttle has become substantially exhausted. Therefore, one feature of the present invention resides in a feeler mechanism for

looms in which the feeler may be held in a retracted or inoperative position with respect to the filling for periods of time and be rendered operative to engage the filling only at intervals, until it detects a near approach to substantial exhaustion of the filling, whereupon the feeler may remain operative and upon detection of substantial exhaustion of filling, set in operation a train of mechanism to replenish the filling.

In carrying out the above feature of the invention, means is provided for engaging the feeler as it is pushed frontwardly by a working supply of filling and for holding the feeler in the retracted position during a number of successive picks of the loom. The feeler is then released to feel the condition of the filling, and if a substantial supply of filling is present, the feeler will be again pushed forward by a working supply of filling and held in the retracted position. It is desirable, however, that the feeler be retracted to a position beyond the position to which it is moved by a working supply of filling as the lay beats up, so that it will be held entirely out of engagement with the filling.

Another feature of the present invention, therefore, resides in a simple means for imparting a further movement to the feeler whereby it will be held entirely out of engagement of the filling as the lay beats up.

Other features of the invention and novel combination of parts in addition to the above will be hereinafter described in connection with the accompanying drawings which illustrate one good practical form thereof.

In the drawings:

Fig. 1 is a perspective view of one side of the loom equipped with a feeler mechanism embodying the present invention;

Fig. 2 is an enlarged plan view of the feeler mechanism showing the feeler in dotted lines in its projected position and in full lines in the position to which it is pushed frontwardly by a working supply of filling;

Fig. 3 is a view similar to that of Fig. 2 but showing the feeler after it has been moved laterally to a position in which it is held entirely out of engagement with the filling;

Fig. 4 is a section view taken on the line 4—4 of Fig. 3; and

Fig. 5 is a perspective view of the detent mechanism of Fig. 2.

The present invention will be described in connection with a feeler mechanism in which the feeler is of the inclined type and enters the shuttle in a direction inclined to the longitudinal axis thereof, and while the advantages of the invention are observable

in connection with such type of feeler, it will be understood that it is not restricted thereto and that the present invention may be employed in connection with other types of feeler mechanism.

The loom frame 1 may be of usual construction comprising the side frames 2 and breast beam 3 on which is secured at either side of the loom a bracket 4 having bearings 10 for the usual transverse or rock shaft 5 which is operatively in control of the replenishing mechanism. It has not been deemed necessary to show and describe the details of the replenishing mechanism because such mechanism may be of any of the well-known types now in common use and the details thereof form no part of the present invention.

Secured to the rock shaft 5 and extending 20 upwardly therefrom is the arm 6 to which is pivotally connected at 7 a rearwardly extending arm 8, the rear end portion of which is adapted to be engaged at times with an operating member 9 which may be formed 25 as part of or associated with the cam follower. In the present instance the arm 8 has pivotally connected to it at 10 a rearwardly extending end portion 11 which is normally out of the path of movement of 30 the operating member 9, and connected to the part 11 is a lug 12 overlying the horizontal arm 13 of a bell crank lever pivoted at 14 to a support 15 secured at 16 to the loom frame. The downwardly extending 35 arm 17 of the bell crank lever is connected to a transmitter 18 which is operatively connected at its other end to a slide 19 under control of the feeler.

Extending from the loom frame is the 40 shipper stand 20 to which is adjustably connected the feeler stand 21 by means of the bolt or set screw 22, as usual.

The feeler 23, as hereinbefore noted, is shown as of the inclined type and is supported upon the feeler stand 21 for movement towards and from the front of the loom. The feeler 23 passes through the bearings at the rear of the feeler stand and also through an opening in the slide 19 which is 50 guided for lateral movement at the rear of the feeler stand, and forward of the rear bearing or guide for the slide the feeler is provided with a bridge or support 24 to which the feeler is secured. Extending 55 forwardly from the bridge 24 is the feeler stem 25 which passes through the swivel block 26 mounted upon the feeler stand by means of a bracket 27, and between the swivel block 26 and the bridge 24 is a spring 60 28 normally tending to move the feeler towards its rearward feeling position. The parts so far described may be substantially the same as the similar parts shown and described more fully in the patent to Edward S. Stimpson, No. 1,309,226, dated July 8,

1919, to which reference may be had for further details of feeler mechanism.

As stated, the present invention contemplates means for holding the feeler retracted for a period of time to a position in which it is completely out of engagement with the filling and for then releasing the feeler to 70 set the condition of the filling within the shuttle.

In carrying out the present invention, the 75 movement of the feeler forward by the pressure of a working supply of filling upon the end of the feeler is utilized to place a spring under tension so that as soon as the pressure of the filling against the end of the feeler is relieved the feeler will be moved by the tensioned spring to a position in which it is entirely out of engagement with the filling and is held in this position for a desired period of time.

Means to this end may be variously constructed and in the embodiment of the invention illustrated a lever 29 is pivotally mounted by a pin 30 at one side of the feeler stand 21 so that the lever extends in the general direction of the feeler 23. The rearwardly extending end of the lever 29 is provided with an inclined surface 31 and with a cam or rounded projection 32, and adjacent this cam or projection is provided a 95 detent 33 which may consist of a block secured to the end of the lever by the screw 34. The detent preferably is provided with a series of teeth 35 that are disposed in a forwardly inclined direction, as 100 shown in Fig. 5. The forwardly extending end of the lever 29 lies within the space between a pair of lugs upon the bracket 36 which bracket is adjustably secured to the feeler stand by the bolt 105 37, and a spring 38 confined between the upper face of the lever 29 and the upper lug of the bracket 36 holds the forward end of the lever normally seated upon the lower lug of the bracket 36. The arrangement is 110 such that the rear end of the lever 29 is normally elevated, as shown in Fig. 1, but may be depressed by compressing the spring 38.

A projecting end of the bridge or support 115 24 is disposed to engage the inclined surface 31 and slide along the same to depress the rear end of the lever 29 as the feeler is pushed forwardly by a working supply of filling in the shuttle, and the projecting 120 end 39 preferably has a beveled lower face 40 which slides along the inclined surface 31. As the projection 39 continues to move forward with the feeler 23 it moves out of engagement with the inclined surface 31 125 into engagement with the cam 32, and the steep inclination of this cam, best shown in Fig. 5, engages the end of the projection 39 and swings the feeler 23 laterally as the rear end of the lever 29 is rocked upwardly under 130

the action of the compressed spring 38. The arrangement is such that as the feeler moves frontwardly it rocks the rear end of the lever 29 downwardly due to the engagement 5 of the projection 39 with the inclined surface 31 but as soon as the projection 39 moves beyond the inclined surface into engagement with the cam 32, the rear end of the lever tends to rise and the cam exerts a 10 pronounced lateral pressure upon the projection 39 which will move the feeler laterally as the pressure of the filling against its rear end is reduced. As the rear end of the lever 29 rocks upwardly one of the teeth 15 35 is moved into position to engage the projection 39 to hold the feeler in a retracted position, but since the cam 32 swings the feeler laterally while the detent 33 is moving into engagement with the projection 39, the 20 lever will be held by the combined action of the cam and detent in the position shown in Fig. 3. From this figure it will be noted that the lateral swinging movement imparted to the feeler 23 serves to move its filling 25 engaging end frontwardly sufficiently to entirely clear the filling as the lay beats up.

The extent to which the feeler is moved frontwardly by a working supply of filling will vary with the amount of filling upon 30 the filling carrier, and since the lower teeth 35 of the detent are disposed frontwardly somewhat of the upper teeth 35 the projection 39 will be engaged by the lower teeth when the filling carrier is full, while it will 35 be engaged by the upper teeth when the greater portion of the filling is used up. When the filling upon the filling carrier becomes nearly exhausted it will not push the feeler frontwardly far enough to cause the 40 projection 39 to engage the detent 32, and as a result the feeler will remain free to feel the condition of the filling upon each detecting beat.

The bracket 36 preferably is provided 45 with an extension 41 to which the lever 29 is secured by the pivot pin 30, and this lever may be accurately adjusted to the desired position upon the feeler stand by means of the adjusting screw 42 which is rotatably 50 mounted in an extension 43 upon the feeler stand and has threaded engagement with the bracket 36 as shown in the drawing. The adjusting screw 42 is rotated by the knurled head 44 and after the bracket 36 is 55 adjusted to the desired position it is secured in place by tightening the bolt 37.

After the feeler has been held inactive for a desired period of time or during the completion of a predetermined number of picks, 60 it should be released to feel the condition of filling within the shuttle and if a sufficient amount of filling is found present the feeler may be again moved to its inactive position by the mechanism described.

65 The means for periodically releasing the

feeler from the detent that holds it retracted may be variously constructed and one good form of means will now be described.

Within the lower lug upon the bracket 36 is provided a sliding plunger which engages 70 the lower face of the lever 29 and an upward thrust of this plunger serves to rock the lever 29 in a direction to disengage the detent 33 from the projection 39 of the feeler, thereby to release the feeler. The plunger 75 just mentioned may be actuated by a wire which is slidably enclosed within the flexible sheath 45 and this sheath in the construction shown extends from the bracket 36 to a bracket 46 adjustably mounted upon 80 the loom frame. Within the bracket 46 is slidably mounted a plunger 47 the projecting end of which is positioned to engage an actuator 48 consisting of a protruding head which may be provided upon each spoke 85 49 of the ratchet wheel 50 which operates the train of gears 51, 52 and 53, that actuate the usual take-up or sand roll. The arrangement is such that as the ratchet wheel 50 rotates, an actuator 48 upon one of the 90 spokes 49 is moved into engagement with the plunger 47 and shoves the plunger laterally. This movement of the plunger 47 is imparted by the wire within the sheath 45 to the plunger within the bracket 36 and the 95 latter rocks the lever 29 in a direction to release the feeler 23.

The lay 54 may be of the usual construction and is provided with a shuttle-box 55, the front wall 56 of which is provided 10 with an opening 57 which, when the shuttle 58 is in the shuttle-box, registers with a corresponding opening 59 formed in the front wall of the shuttle. The shuttle-box and shuttle may be of the construction now common in feeler looms, the essential being that a proper opening be provided for the entrance of the feeler into the shuttle to feel for the filling when the feeler is active on a detecting beat.

From the foregoing description it will be apparent that the present invention provides simple means for moving the feeler to a position in which it is entirely out of the reach of the filling within the shuttle, 115 and for holding the feeler inactive for a period of time, and for releasing the feeler at intervals that it may detect the condition of the filling within the shuttle.

The cam 32 is so constructed and arranged 120 with respect to the teeth of the detent 33 and the feeler projection, that when the cam engages the feeler projection and effects lateral movement of the feeler, the latter will be swung in a short arc around the front bearing of the feeler as a center and moved frontwardly in said arc a sufficient distance to clear the filling on the subsequent detecting beats, where it will be held by the teeth of the detent until released by the take-up 130

mechanism to again perform its detecting function. The lateral movement of the feeler under the action of the cam 32 is not sufficient to call the change of filling but is sufficient to move the feeler to an inoperative position, so that on subsequent picks it will not contact with the filling until released from the detent.

What is claimed is:

- 19 1. An intermittent feeler mechanism for looms, comprising, in combination, a feeler mounted to enter a shuttle and detect substantial exhaustion of the filling, a detent mounted at one side of the feeler to hold the latter in retracted position, a projection upon the feeler that engages the detent, a cam positioned to be engaged by said projection when the feeler is pushed forwardly by a working supply of filling and operable to swing the feeler laterally to an inoperative position as the projection engages the detent, and means actuated periodically upon the completion of a predetermined number of picks for releasing the feeler from the detent.
- 20 2. An intermittent feeler mechanism for looms, comprising, in combination, a feeler mounted to detect substantial exhaustion of the filling within a shuttle, a detent for holding the feeler in a retracted position, a cam positioned to act upon the feeler when the latter is pushed forwardly by a working supply of filling and constructed and arranged to swing the feeler laterally to an inoperative position beyond the reach of the filling in the shuttle on subsequent detecting beats where it is held by the detent, and means operable periodically upon the completion of a multiplicity of picks for releasing the feeler from the detent.
- 25 3. An intermittent feeler mechanism for looms, comprising, in combination, a feeler mounted to detect substantial exhaustion of the filling within a shuttle, a detent for holding the feeler in a retracted position, means upon the feeler that engage the detent, a cam positioned to act upon the feeler when the latter is pushed forwardly by a working supply of filling and operable to swing the feeler laterally to an inoperative position as said means engages the detent, and means operable periodically upon the completion of a multiplicity of picks for releasing the feeler from the detent.
- 40 4. An intermittent feeler mechanism for looms, comprising, in combination, a feeler mounted to detect substantial exhaustion of the filling within a shuttle, a detent for holding the feeler in a retracted position, a projection upon the feeler that engages the detent, spring actuated means for acting upon the feeler when the latter is pushed forwardly by a working supply of filling and operable to swing the feeler laterally to an inoperative position as the projection en-

gages the detent, and means operable periodically upon the completion of a multiplicity of picks for releasing the feeler from the detent.

5. An intermittent feeler mechanism for looms comprising, in combination, a feeler mounted to detect the substantial exhaustion of the filling in a shuttle, a detent for holding the feeler in a retracted position, a projection upon the feeler that engages the detent, means constructed and arranged to act laterally upon the feeler when the latter is pushed forwardly by a working supply of filling and operable to move the feeler laterally to an inoperative position beyond the reach of the filling that it may be held in such position by the detent during its periods of inactivity, and means operable periodically upon the completion of a multiplicity of picks for releasing the feeler from the detent.

6. An intermittent feeler mechanism for looms, comprising, in combination, a feeler mounted to detect the substantial exhaustion of filling in a shuttle, a detent having teeth for holding the feeler in different retracted positions, a projection upon the feeler engageable with the different teeth, a cam secured adjacent said teeth to be engaged by the projection when the feeler is pushed forwardly by a working supply of filling and operable to force the feeler laterally to an inoperative position as the projection moves into engagement with one of said teeth, and means operable periodically upon the completion of a multiplicity of picks for releasing the feeler from the detent.

7. An intermittent feeler mechanism for looms, comprising, in combination, a feeler mounted to detect the substantial exhaustion of filling in a shuttle, a lever extending in the general direction of the feeler and pivotally mounted for rocking movement, a detent upon the lever for holding the feeler in its retracted position, a cam upon the lever and constructed and arranged to act upon the feeler when the latter is pushed forwardly by a working supply of filling and operable to force the feeler laterally to an inoperative position as it moves into position to be engaged by said detent, and means operable periodically upon the completion of a multiplicity of picks for releasing the feeler from the detent.

8. An intermittent feeler mechanism for looms, comprising, in combination, a feeler mounted to detect the substantial exhaustion of filling in a shuttle, a detent for holding the feeler in a retracted position mounted for yielding downward movement and having an inclined surface leading to the toothed portion of the detent, a projection upon the feeler that engages said inclined surface and depresses the detent as the feeler is pushed forwardly by a working supply of

filling and then releases the detent to engage the projection, a cam upon said detent operable to push the feeler laterally to an inoperative position as the projection is engaged by the detent, and means operable periodically upon the completion of a multiplicity of picks for releasing the feeler from the detent.

9. An intermittent feeler mechanism for looms, comprising, in combination, a feeler mounted to detect the substantial exhaustion of filling in a shuttle, a lever pivotally mounted for rocking movement and having a detent for holding the feeler in its retracted position, a cam upon the lever constructed and arranged to be depressed by the feeler as the latter is moved to its forward position by a working supply of filling and operable to swing the feeler laterally to an inoperative position as the detent moves into the feeler holding position, and means operable periodically upon the completion of a multiplicity of picks for releasing the feeler from the detent.

10. An intermittent feeler mechanism for looms, comprising, in combination, a feeler mounted to detect substantial exhaustion of filling within a shuttle, a detent for holding the feeler in a retracted position, a projection upon the feeler that engages the detent, means constructed and arranged to act upon the feeler when the latter is pushed by a working supply of filling to its forward position and operable to move the feeler laterally to an inoperative position as the projection is engaged by the detent, a take-up mechanism, and means actuated by the take-up mechanism for periodically releasing the feeler from the detent.

11. An intermittent feeler mechanism for looms, comprising, in combination, a feeler mounted to detect substantial exhaustion of the filling within a shuttle, a detent for holding the feeler in a retracted position, a projection upon the feeler that engages the detent, yielding means constructed and arranged to be displaced by the feeler as the latter is pushed forwardly by a working supply of filling and operable to impart an additional forward movement to the feeler as the projection is engaged by the detent, and means operable periodically upon the completion of a multiplicity of picks for releasing the feeler from the detent.

12. An intermittent feeler mechanism for looms, comprising, in combination, a feeler mounted to detect substantial exhaustion of the filling within a shuttle, a detent for holding the feeler in a retracted position, a projection upon the feeler that engages the detent, means having a spring that is placed under tension by the feeler as the latter is pushed forwardly by a working supply of filling and operable by the tensioned spring to move the feeler entirely clear of the fill-

ing as said projection is engaged by the detent, and means operable periodically upon the completion of a multiplicity of picks for releasing the feeler from the detent.

13. An intermittent feeler mechanism for looms, comprising, in combination, a feeler mounted to detect substantial exhaustion of the filling in a shuttle, a detent for holding the feeler in a retracted position, a cam positioned to act upon the feeler when the latter has been pushed forwardly by a working supply of filling in the shuttle on a detecting beat and constructed and arranged to swing the feeler laterally to an inoperative position beyond the reach of the filling, and means operable periodically for releasing the feeler from the detent.

14. In a feeler mechanism for looms, the combination of a feeler, a spring normally impelling the feeler towards its rearward position, a part connected to the feeler and having a detent engaging member, a detent for engaging said member, the engaging surfaces of said member and detent being relatively inclined in a direction transversely of the loom and constructed and arranged to cause the feeler to be moved laterally under the influence of said spring when the detent engaging member and detent are engaged as the lay goes back after a detecting beat.

15. In a feeler mechanism for looms, the combination of a feeler, a spring normally acting in a direction to move the feeler towards feeling position, a detent for holding the feeler in forward or non-feeling position, and interengaging members carried by the feeler and detent and having their engaging surfaces relatively inclined in a direction transversely of the loom to effect lateral movement of the feeler under the influence of the feeler spring when said surfaces are engaged as the lay goes back.

16. In an intermittent feeler mechanism for looms, the combination of a feeler mounted to detect substantial exhaustion of the filling on a detecting beat, a detent for holding the feeler in retracted front position, a projection connected to the feeler for engaging the detent, said projection and detent having their engaging surfaces constructed and arranged to cause the feeler to be moved laterally into an inoperative position when the lay goes back and the projection and detent are engaged.

17. In an intermittent feeler mechanism for looms, the combination of a feeler mounted to detect substantial exhaustion of the filling on a detecting beat, a detent for holding the feeler in retracted front position, a projection connected to the feeler for engaging the detent, said projection and detent having their engaging surfaces constructed and arranged to cause the feeler to be moved laterally into an inoperative position when the lay goes back and the projec-

tion and detent are engaged, and means for periodically releasing the feeler from the detent that it may perform its feeling function.

18. In a feeler mechanism for looms, the combination of a feeler mounted to enter the shuttle on a detecting beat in a direction inclined to the longitudinal axis of the shuttle, a spring for normally impelling the feeler rearwardly, a detent for holding the feeler in frontward retracted position, a projection carried by the feeler for engaging the detent when the feeler is moved frontwardly by a working supply of filling, the intervening surfaces of the projection and detent being relatively inclined to effect lateral movement of the feeler to an inoperative position that it may not injuriously contact with the filling on subsequent detecting beats, and means for automatically releasing the feeler from the detent from time to time to

detect the condition of the filling and effect replenishment when the filling is substantially exhausted.

19. In an intermittent feeler mechanism for looms, the combination of a feeler to detect the condition of the filling in the shuttle, a detent for holding the feeler in an inoperative position during its periods of inactivity and for freeing the feeler at intervals to its periods of activity, and means for moving the feeler laterally to a position beyond the reach of the filling on detecting beats that it may be held in such position by the detent during its periods of inactivity, and means for freeing the feeler from the detent at intervals. 25 30 35

In testimony whereof, I have signed my name to this specification.

EDWARD S. STIMPSON.
